United States Patent Office

Des. 200,185
Patented Jan. 26, 1965

200,185

AIRCRAFT

William Coelho Thomas, 11083 Cloverlawn,
Detroit, Mich.

Filed Jan. 23, 1963, Ser. No. 73,440

Term of patent 14 years

(Cl. D71—1)

FIG. 1

FIG. 2

FIG. 5

FIG.3

FIG.4

FIGURE 1 is a top perspective view of an aircraft embodying my new design.

FIGURE 2 is a side elevation view of the aircraft.

FIGURE 3 is a front elevation view of the aircraft.

FIGURE 4 is a rear elevation view of the aircraft.

FIGURE 5 is a cross-sectional view taken on line 5—5 of FIG. 1.

This application is a continuation-in-part of application Serial No. D-64,330 filed March 7, 1961, and now abandoned.

I claim:

The ornamental design for an aircraft, substantially as shown and described.
